UNITED STATES PATENT OFFICE.

FRANK B. CHURCHILL, OF LA HARPE, ILLINOIS.

POWER ATTACHMENT FOR WASHING-MACHINES.

1,227,388.

Specification of Letters Patent. Patented May 22, 1917.

Application filed November 10, 1913. Serial No. 800,182.

To all whom it may concern:

Be it known that I, FRANK B. CHURCHILL, a citizen of the United States, residing at La Harpe, in the county of Hancock and State of Illinois, have invented a new and useful Power Attachment for Washing-Machines, of which the following is a specification.

The invention relates to gearing for operating washing machines and wringers.

The object of the present invention is to provide simple, efficient and comparatively inexpensive gearing of strong and durable construction designed for vibrating rocking washing machine bodies, more especially that shown and described in Patent No. 981,169 granted to me Jan. 10, 1911, and capable of actuating a superimposed wringer and equipped with clutch and shifting mechanism for enabling either the washing machine or the wringer to be instantly thrown into and out of operation.

With these and other objects in view, the invention consists in the construction and novel combination of parts hereinafter fully described, illustrated in the accompanying drawings, and pointed out in the claims hereto appended; it being understood that various changes in the form, proportion, size and minor details of construction, within the scope of the claims, may be resorted to without departing from the spirit or sacrificing any of the advantages of the invention.

In the drawings:

Figure 1 is a perspective view of a washing machine and wringer equipped with gearing, constructed in accordance with this invention.

Fig. 2 is a horizontal sectional view through the lower portion of the same.

Fig. 3 is a vertical longitudinal sectional view through the lower portion of the washing machine.

Fig. 4 is an elevation of the wringer, the removable section of the upper gear case being detached.

Fig. 5 is a detail view of the catch or keeper for holding the clutch operating lever.

Like numerals of reference designate corresponding parts in all the figures of the drawings.

In the accompanying drawings in which is illustrated the preferred embodiment of the invention, 1 designates a substantially

oblong base composed of horizontal side and end bars and provided with relatively short corner legs 2. The side bars receive and support rockers 3 of an oscillatory or vibratory washing machine body or receptacle 4, which rocks in a direction longitudinally of the base, being retained thereon by central and side arms 5 and 6 projecting below the lower edges of the rockers and arranged to extend into central and side recesses 7 and 8 of the base. The central and side recesses 7 and 8 are formed by bars or cleats secured to the inner faces of the sides of the base, and the central and side arms prevent lateral displacement of the rockers. The lower ends of the arms 5 and 6 are preferably rounded, as clearly illustrated in Fig. 3 of the drawings, and in the oscillation of the washing machine body the end arms are carried alternately into and out of engagement with the terminal recesses 8, while the central arms 5 remain in the recesses 7 at all times. Rising from the side bars of the base at points intermediate of the ends thereof, are vertical standards 9 supported by inclined braces 10 and connected at their upper ends by a wringer supporting bar 11 to which a wringer 12 is detachably secured by clamps 13 or other suitable means. As the particular construction of the washing machine body and the wringer does not constitute a portion of the present invention, a detail description of the same is deemed unnecessary.

Motion is communicated to the washing machine body 4 by means of a walking beam or lever 14, pivotally mounted on a transverse rod or shaft 15 and composed of opposite longitudinal arms 16 and 17 and an upwardly extending arm 18. The walking beam or lever, which is preferably constructed of flanged metal, is provided with a central integral sleeve or hub portion 19 to receive the transverse pivot shaft, and it is secured thereto in fixed adjustment by means of a set screw 20, but any other suitable means may, of course, be employed for maintaining the walking beam or lever in walking position on the shaft or pivot rod 15. The shaft or pivot rod 15 is journaled in a suitable bearing 20 at one side of the base, and it is supported at the other side of the base by a substantially rectangular bearing frame 21. The bearing 20 and the bearing frame extend beneath and form bottoms for the central recesses 7. The arms 16 of the walking beam or lever is

bent or bowed laterally to clear a crank disk 22, and it is connected at its outer end by a link rod 23 with one end of the washing machine body 4. The washing machine body 4 is provided with a channel plate 24 preferably consisting of a casting and fitting an end transverse bar 25 of the washing machine body and provided with spaced depending ears 26 between which the upper 5 end of the link rod 23 is pivoted. The lower end 27 of the link rod is enlarged and bifurcated and it straddles and is pivoted to the outer terminal portion of the arm 16 of the walking beam or lever. The other 10 arm 17 of the walking beam or lever is provided with a pivoted loop or shackle 28, which is connected to the lower end of a coiled spring 29, and the latter yieldably connects the washing machine body with 15 the arms 17 of the walking beam or lever. The upper end of the coiled spring is secured in an eye 30 of a channel plate or piece 31, which is bolted or otherwise fastened to the adjacent transverse bar 32 of 20 the washing machine body. The link rod forms a positive connection between one end of the washing machine body and the coiled spring constitutes a yieldable connection between the walking beam and the other 25 end of the washing machine body, and the connecting means is adapted to conform to the constantly shifting of the fulcrum point of the rockers on the base of the washing machine and permits an easy operation of 30 the washing machine without straining the parts. The spring also assists in holding the rockers to the base and prevents them from 35 jumping thereon.

The arm 18, which extends upwardly from the central portion of the walking beam or lever, has a forked or bifurcated upper end 33, which is pivoted to the upper end of a pitman 34 extending downwardly and outwardly from the intermediate arm 18 to a 40 wrist pin 35 of the crank disk 22, whereby when the crank disk is rotated, the walking beam or lever will be oscillated for rocking the washing machine body on the base. Any other preferred form of crank element may, 45 of course, be employed, and the said crank disk is mounted on an inner or rear section 36 of a transversely disposed transmission shaft composed of the said inner or rear section 36, and a front or outer section 36^a. The front or outer section 36^a carries a spur gear wheel 37 fixed to the front section 36^a by a key, clamping screw, or other suitable fastening means and meshing with a pinion 38 of a driving shaft 39. The driving 50 and transmission shafts are journaled in suitable bearings of the frame 21, which is composed of spaced sides and integral connecting end portions, one of the sides of the bearing frame being secured to the adjacent 55 side of the base and the bearing frame be-

ing provided at the opposite side with a longitudinally disposed arm 40, which is secured to one end of the base. The bearing frame 21 which is preferably flanged as shown, is located adjacent to one corner of the base, as clearly illustrated in Fig. 2 of the drawings, and it extends beneath the adjacent side and end bars of the base and is provided with upwardly projecting ears or flanges 41 arranged at the said side and 70 end bars of the base and pierced by bolts or other suitable fastening means, which secure the bearing frame to the base. The driving shaft 39 projects from one side of the base and has mounted on it a driving 75 pulley 42, which is designed to be connected by a belt with a suitable motor or engine.

The gear wheel 37 which is continuously rotated when the driving shaft is actuated, has an extended hub 42^a receiving the adjacent ends of the front and rear sections of the transmission shaft, the inner ends of the sections being illustrated in the drawings as slidably supported in order to show the construction more clearly, but in practice the sections will substantially meet. The extended hub 42^a is provided at the 80 end with a clutch face 43 adapted to interlock with a coacting clutch face 44 of a clutch section 45 slidably connected with the inner 85 or rear section of the transmission shaft by a key, or other suitable fastening means. The clutch section 45 is provided with an annular groove 46, which is engaged by a forked portion 47 of a clutch operating 90 lever 48, fulcrumed at a point intermediate of its ends on an arm 49 of the bearing frame and having its outer end arranged within a slot 50 of a catch or keeper 51, mounted on one end of the base and provided at the terminal portions of the slot with notches 52, adapted to receive the clutch operating lever for holding the 95 slideable clutch section into and out of engagement with the clutch face of the gear wheel 100 37. The clutch lever is extended beyond the catch or keeper and its outer terminal portion constitutes a grip or handle. When the slideable clutch section 45 is engaged with the clutch face of the gear wheel 37, 105 the yielding beam is actuated and oscillates 110 the washing machine body on the base.

The front section 36^a of the transmission shaft projects outwardly beyond the base and extends into a lower gear case 53, and 120 carries a vertical bevel pinion 54 keyed or otherwise fixed to the front section of the transmission shaft, so as to be continuously rotated when the driving shaft is actuated. The vertical bevel pinion 54 meshes with a 125 horizontal bevel pinion 55 secured to the lower end of a vertical shaft 56. The gears 54 and 55 are housed within the lower gear case 53, which constitutes a bearing for the lower portion of the vertical shaft 56, and 130

the latter is journaled at its upper portion in an upper gear case 57. The upper end of the vertical shaft 56 carries a horizontal vertical gear 58, arranged between and adapted to mesh with either one of a pair of vertical bevel pinions or gears 59, mounted on an extension 60 of the lower roll 61 of the wringer. The vertical bevel pinions 59 are preferably formed integral with the sleeve 62, slidably interlocked with the shaft of the lower wringer roll 61 and adapted to be shifted along the same to carry either of the gears 59 into mesh with the gear 58 and the vertical shaft and also to arrange both of the gears 59 out of mesh with the gear 58. By this construction the lower wringer roll is adapted to be rotated in either direction and also to be thrown out of operation when desired. The gears 58 and 59 are housed within the upper gear case, which is provided with a removable section 63. The sleeve 62 is provided with a central annular groove 64 preferably formed by spaced annular flanges and engaged by a forked portion 65 of a clutch operating lever 66, extending upwardly from the sleeve 62 and fulcrumed at an intermediate point in the gear case by a pin 67 or other suitable pivot and connected at its upper end with an operating rod 68. The operating rod 68 extends across the top of the wringer and is supported at the opposite side thereof from that at which the gearing is located by a link or lever 69, pivoted at its lower end 70 to a lug or projection of the wringer and pivotally connected at its upper end to the adjacent end of the operating rod 68. The operating rod 68 is adapted to be shifted longitudinally to throw the gears 59 into and out of mesh with the gear 58. By means of the shifting mechanism at the wringer and the clutch operating mechanism at the base of the washing machine, either the wringer or the washing machine may be thrown into and out of operation.

Instead of constructing the transmission shaft in two sections, a continuous shaft extending entirely across the bearing frame 50 may be employed, the crank element being secured to the inner or rear end of the same and the lower gear 37 and the pinion 54 being connected by a sleeve and rotating on the front portion of the transmission shaft. With this construction, the lower clutch will operate to connect the transmission shaft with the lower gearing to throw the washing mechanism into and out of operation.

60 What is claimed is:-

1. In combination with an active mechanism including a vibratory member, a walking beam pivotally mounted below the vibratory member, means for connecting one arm 65 of the walking beam with one end of the

vibratory member, yieldable means for connecting the other arm of the walking beam with the other end of the said member, and means for oscillating the walking beam.

2. In combination with an active mechanism including a vibratory member, a walking beam or lever pivotally mounted at an intermediate point, a link connecting one arm of the walking beam or lever with one end of the vibratory member, yieldable means for connecting the other arm of the walking beam or lever with the other end of the said member, and gearing for oscillating the walking beam or lever.

3. In combination with an active mechanism including a vibratory member, a walking beam or lever fulcrumed at an intermediate point beneath the said member, a link connecting one arm of the walking beam or lever with one end of the member, a coiled spring connecting the other arm of the walking beam or lever with the other end of the said member, and gearing connected with the walking beam or lever for oscillating the same.

4. In combination with an active mechanism including a vibratory member, a walking beam or lever fulcrumed at an intermediate point, a link connecting one arm of the walking beam or lever with one end of the said member, yieldable means for connecting the other arm of the walking beam or lever with the other end of the member, a crank element, a pitman connecting the crank element with the walking beam or lever, and gearing for rotating the crank element.

5. In combination with an active mechanism including a vibratory member having supporting rockers, a walking beam or lever pivoted at a point intermediate of its ends and provided at the pivotal point with a projecting arm, a link connecting one end of the walking beam or lever with one end of the said member, yieldable means for connecting the other end of the walking beam or lever with the other end of the member, a crank element, a pitman extending from the crank element to the said arm of the walking beam or lever, and gearing for rotating the crank element.

6. In combination with an active mechanism including a vibratory member, a walking beam or lever pivoted at an intermediate point beneath the said member to form opposite longitudinal arms and provided at the pivotal point with an intermediate projecting arm, a link connecting one of the longitudinal arms with the said member, yieldable means for connecting the other longitudinal arm of the walking beam or lever with the member, a driving shaft, a transmission shaft, gearing connecting the said shafts, a crank element mounted on the transmission shaft, and a pitman connecting

the crank element with the intermediate arm of the walking beam or lever.

7. In combination with an active mechanism including a base, and a vibratory body having supporting rockers mounted on the base, a bearing frame secured to the base at one side thereof, a walking beam or lever pivotally mounted at an intermediate point within the base and arranged between the bearing frame and the opposite side of the base and having an intermediate projecting arm, a link connecting one of the longitudinal arms of the walking beam or lever with the body, yieldable means for connecting the yieldable body with the other longitudinal arm of the walking beam or lever, trans-

versely disposed transmission and driving shafts supported by the bearing frame, gearing connecting the said shafts, a crank element mounted on the transmission shaft and arranged at the inner side of the bearing frame, and a pitman connecting the crank element with the intermediate arm of the walking beam or lever.

In testimony, that I claim the foregoing as my own, I have hereto affixed my signature in the presence of two witnesses.

FRANK B. CHURCHILL.
